United States Patent

Des. 237,182
Patented Oct. 14, 1975

237,182

BATHTUB

Robert I. Rosenhaus, 1805 NE. 118th Road,
North Miami, Fla. 33161

Filed Aug. 12, 1974, Ser. No. 496,531

Term of patent 3½ years

Int. Cl. D23—02

U.S. Cl. D23—55

Fig. 1

Fig. 2

FIG. 3

FIG. 4

FIG. 1 is a perspective view of a bathtub showing my new design.

FIG. 2 is a top plan view thereof.

FIG. 3 is a side elevational view thereof.

FIG. 4 is a vertical cross section along line 4—4 of FIG. 2.

I claim:

The ornamental design for a bathtub, substantially as shown.
